UNITED STATES PATENT OFFICE.

ANDREW LITTLE, OF NEW YORK, N. Y.

DESIGN FOR TYPE.

SPECIFICATION forming part of Design No. 16,182, dated July 28, 1885.

Application filed May 29, 1885. Term of patent 7 years.

To all whom it may concern:

Be it known that I, ANDREW LITTLE, of the city, county, and State of New York, have invented, made, and produced a new Design for 5 a Font of Printing-Type, of which the following is a specification.

The nature of my design is clearly shown in the accompanying typographic impression, to which reference is made; and it consists of a 10 letter formed of the heavy curved lines, as shown, ornamented upon the right hand, left hand, above, and below by a series of light curved lines, some of which are semi-elliptical, and present the appearance of tendrils. 15 like ornaments surrounding the letter proper. The faces of the A, B, D, E, H, K, M, N, O,

P, Q, R, U, V, W, X, Y, and Z are ornamented by the light curved line figures, as shown. The cross-lines of the A, B, E, and H extend beyond the heavy curved portion of the letter 20 upon the left and curve downward.

Having now described my invention, I claim as new—

The design for a font of printing-type, consisting of a letter formed of the heavy curved 25 lines surrounded by the light curved line groundwork and flourishes, as shown and described.

ANDREW LITTLE.

In presence of—

WILLIAM V. H. HICKS,
A. SIDNEY DOANE.
